UNITED STATES PATENT OFFICE.

JOSEPH PHILLIPS, OF CINCINNATI, OHIO.

OPEN-AIR SLEEPING-COMPARTMENT.

980,433.

Specification of Letters Patent.

Patented Jan. 3, 1911.

Application filed September 9, 1909. Serial No. 516,917.

To all whom it may concern:

Be it known that I, JOSEPH PHILLIPS, a citizen of the United States of America, and resident of Cincinnati, county of Hamilton, 5 State of Ohio, have invented certain new and useful Improvements in Open-Air Sleeping-Compartments, of which the following is a specification.

The plague tuberculosis, being the immediate cause of so large a proportion of the deaths of people in this and other countries, has spurred men of science to a study of the character of the disease, and of 10 methods of preventing it, and of curing it, 15 of which methods that known as the open air treatment has had so large a success, that it receives almost universal indorsement. One of the features of this treatment is sleeping in the open air. This has caused 20 many people, even such as have no symptoms of the disease, to build permanent open air sleeping compartments upon their houses. This however entails a large outlay of 25 money, and in many instances detracts from the usefulness of the room upon the exterior of which the compartment is built.

It is the object of my invention to provide a compartment which may be installed at comparatively small expense, may be 30 lapsed readily so as not to obstruct light and air to the room upon the external walls of which it is placed, and also may readily be prepared for occupancy. This object is 35 attained by the means described in the specification and illustrated in the accompanying drawings, in which:—

Figure 1 is a perspective view of a compartment embodying my invention, in position for use. Fig. 2 is a similar view of it, 40 when folded against the wall of the building. Fig. 3 is a sectional view upon line 3—3 of Fig. 1. Fig. 4 is a detail end view of the folding bed, and of the bottom of side wall of the compartment, the dotted 45 lines showing the bed as folded during the day. Fig. 5 is a detail view, showing in end elevation the floor partially folded. Fig. 6 is a detail view of the floor folded and in its horizontal position, and of the 50 instruments for effecting the movement of the floor and its supporting brackets. Fig. 7 is a detail perspective of part of a supporting bracket and the instrument for rotating it to its operative and inoperative 55 position. Fig. 8 is a sectional view taken upon line 8—8 Fig. 3, upon an enlarged

scale. Fig. 9 is a sectional view taken upon line 9—9 of Fig. 1. Fig. 10 is a detail perspective view of the floor, one half thereof only being shown, and the floor being shown 60 in its expanded position with the frame of a folding bed shown located upon it. Fig. 11 is a perspective view of the floor and the bed showing them partially folded. This view shows the half of the floor and the bed, 65 which is not shown in Fig. 10.

I will describe the floor construction, then the sides and front, and then the roof or canopy.

The floor consists of three longitudinal 70 panels A, A' and A². Panels A and A² have upon their sides and ends upturned flanges a' a² a³, and panel A' has upon its ends flanges a⁴. Panels A and A² are hinged to panel A' at a⁵ and a⁶ and connecting the flanges a' 75 and a² are two links a⁷—a⁸ which are pivoted together. Panel A' is of a width equal to the combined heights of flanges a' and a², so that the bottom may be folded into the shape of a closed box, with flanges a² resting 80 upon flanges a', flange a² resting upon flange a, and panel A' forming the side of the box opposite flanges a a³. Panels A, A² have longitudinal eye beams a⁹, a¹⁰, a¹¹, a¹² secured to them. Panel A has secured to it 85 journal sleeves a¹³, a¹⁴, a¹⁵ which engage horizontal rods a¹⁶ which are secured to the wall of the building beneath a window. Beneath rods a¹⁶, there are secured to the building journal plates b b' upon which 90 brackets B B' are hinged. Brackets B, B', carry blocks or sections of eye beams b², b³, b⁴, which are adapted to fit under eye beams a¹⁰, a¹¹, a¹². Brackets B B' having projecting from them sockets b⁵ into which the 95 square end of a crank B² may be inserted, through holes in the window ledge, as shown in Fig. 2, to rotate the brackets to their operative or inoperative positions. Eye beams a¹¹, a¹² having holes in their flanges, through which a rod A³ may be inserted, as illustrated in Fig. 2 to raise the floor from a pendent to a horizontal position. After the floor has been raised, brackets B B' may be 100 swung outward, beneath it by means of crank B². The bar A³ and the crank B² are then removed from the floor and the brackets respectively and stored away. 105

There are two parts which constitute the ends and the side of the compartment. Since these parts are the same in construction I will describe but one of them in detail. Each of 110

said parts consists of four frames D D' D² and D³ which are hinged together at d d' d² d³. Each frame is made substantially rectangular, and has an intermediate cross bar, such as a cross bar d⁴ of frame D. Between the intermediate cross bars and the bottoms and tops respectively of the frames secondary frames D⁴ D⁵ are hinged in each main frame. These secondary frames may 10 have lattices or screens secured to them, or in case it is desired to make a sun-parlor may be closed with glass. Panels D D' have enlarged tapered tops d⁵ d⁶. Panels D are secured to the wall of the house in the following manner:—Journal plates E E' shown in Fig. 2 are secured to the wall of the house. Sockets e e' are hinged to the inner edges of panel D. Rod e² is secured in the journal plates E E', and this rod passes through the 20 sockets e e'. The panel D may be rotated about this rod e². To brace the panels D D' in their expanded position I utilize a series of links g which are pivoted together at their centers and ends. The two inner links 25 are pivoted to sockets g' g², which are journaled upon the rod e². The link g³ has a foot g⁶ with down-turned and inturned flanges, which are adapted to engage angle plates g⁴ g⁵ which are secured to the outer 30 ends of flanges a² of the panel A² of the floor. One of the panels D³ has a hook h which engages an eye h' of the other panel D³ when the panels have been expanded so as to meet as shown in Fig. 1. The roof or canopy K is 35 secured to the wall immediately upon the panels D, and has a suitable pole k secured to its free side.

I will now describe the bed and the manner of mounting it upon the floor:—The 40 ends of the bed frame M consist of two bars m m' hinged together at m². To the end of the bar m a leg m³, is hinged so as to be capable of being folded inward as illustrated in Fig. 10. To the outer end of the 45 bar m, a leg m⁴ is pivoted; said leg has pivoted to it a brace rod m⁵ which is slotted at m⁶ to engage pin m⁷ which is secured to the bar m. The bar m' is pivoted to the panel a² by means of links m⁸, m⁹ as shown in 50 Fig. 11.

The operation of the parts are as follows:—Suppose the compartment to be collapsed and folded as illustrated in Fig. 2. The floor is raised by means of the rod A³ 55 and the brackets are swung outward by means of the crank B². When the brackets B B' are thus swung outward, they become locked in position by engaging the lugs a¹⁸, a¹⁹ upon the bottom of the eye beam a¹². The panels D D', D², D³, are then swung 60 outward toward the floor, and are opened out so that the panels D D' stand adjacent to the ends of the floor. The pivoted links

g are then expanded and feet g⁴ of the links g³ are engaged with the angle irons g⁴, g⁵. 65 Then the panels D², D³ at each end of the floor are swung inward and the panels D³ are secured together to complete the side of the compartment. Then the canopy is unrolled to the position shown in Fig. 1. The 70 flange a is laid flat upon the sill so as not to form an obstruction to those persons who may be passing in and out of the compartment. In folding the compartment the operations are the reverse of those just described. In folding the bed the frame is folded about the hinges m² so that the bars m rest upon the bars m'. When the floor has been folded the bed rests within the box 75 formed by the panels and their flanges. 80

What I claim is:—

1. A compartment of the character described, comprising folding panels secured to a vertical wall and co-operating to form a side and end walls of the compartment, a 85 folding floor hinged to the vertical supporting wall of the panels, brackets hinged to the supporting wall for holding said floor in an operative position, links for engaging the floor and holding the panels in place, 90 and means for locking the panels together and in an operative position.

2. A compartment of the character described, comprising panels hinged together in two sets and pivotally mounted on a vertical supporting wall, a floor hinged to the supporting wall and movable to an operative and inoperative position, brackets for supporting the floor in the operative position, links for engaging said floor and for 100 holding the panels forming the ends of the compartment in place, means for locking the sets of the two panels together and in an operative position, and a folding cover for said compartment engaging the tops of said 105 panels.

3. A compartment of the character described comprising panels hinged together in two sets and pivotally mounted on a vertical supporting wall, a floor pivotally 110 mounted on the supporting wall and movable to an operative and an inoperative position, brackets pivotally mounted on the supporting wall for supporting the floor, extendible links for engaging said floor and for holding said panels in place, means for moving said floor to the operative or inoperative position, means for moving said brackets, means for locking the two sets of panels together in an operative position, and a 115 folding cover for the compartment.

JOSEPH PHILLIPS.
